APPARATUS FOR WASHING DISHES,
SILVERWARE, AND THE LIKEDonald E. Yochem, Columbus, Ohio, assignor to
L. S. D. Inc., Dayton, Ohio, a corporation of
Ohio

Application December 19, 1938, Serial No. 246,702

6 Claims. (Cl. 299—63)

This invention relates to new and useful improvements in apparatus adapted for washing, rinsing, and/or drying such objects as dishes, silverware, glassware, and the like. More particularly, it relates to apparatus employed for impelling, washing, rinsing, and drying fluids throughout the interior of a housing or casing in which the objects to be treated are confined. The various fluid impelling mechanisms embodying this invention may be considered as modifications of the impelling mechanism disclosed and claimed in my Patent No. 2,137,971, issued November 22, 1938.

In my aforesaid patent I have not only disclosed fluid impelling means but I have also disclosed a rack structure which is capable of supporting different styles and types of dishes, glassware, silverware, and the like in a very efficient and effective manner so as to take full advantage of the movement of the treating fluids in the various portions of the housing interior; means for supplying the housing with the required amount of treatment fluid; means for readily draining the treatment fluid from the housing; and power means for driving the impeller mechanism. It is to be understood that the various impeller mechanisms embodying this invention are to be employed in combination with the additional apparatus disclosed in my patent, or its equivalent.

Impeller mechanism for dish washing machines of the prior art may be arranged generally in two groups. One of these groups involves rotatable impeller means having its axis arranged vertically. The other group involves rotatable impeller means having its axis arranged horizontally.

Impeller mechanism of the first group, having vertical axes of rotation, operate most effectively in combination with housings which are of circular or cylindrical formation in top plan. This type of impeller mechanism can be designed so that the treatment fluid can be uniformly distributed throughout the interior of the cylindrical housing. This type of impeller mechanism, however, possesses several undesirable features of construction. For example, a cylindrical housing cannot be employed to the best advantage in confining dishes, silverware, and the like. Impeller mechanism having a vertical axis of rotation must be associated with the bottom wall of the housing, and it is necessary, therefore, to provide and maintain a water-tight joint between the bottom wall of the housing and the bearing for the impeller shaft which must pass through said bottom wall. The impeller must be submerged

5 to a considerable extent in the treatment fluid and the impeller, therefore, operates to either splash or project the treatment fluid in dense or concentrated form. It has been determined that for the most effective action the treatment fluid should be projected in a finely atomized condition and with the particles traveling at a very high velocity. It has been found to be impossible to obtain this type of action with a rotatable impeller which is submerged to an appreciable extent in the treatment fluid and which is rotated about a vertical axis.

An impeller device of the second group; i. e. an impeller rotating about a horizontal axis, is usually associated with a housing or casing of rectangular or square shape in top plan. Housings of this shape or design are capable of confining more effectively a larger number of dishes, and the like, to be treated. It, also, is possible to operate an impeller device of this character so that its blades will merely dip from a trough a comparatively small amount of treatment fluid and disperse this fluid in a finely atomized condition and at a high velocity into the treatment zone of the housing. Prior art impeller devices of this type, however, possess the very serious disadvantage of being unable to project the treatment fluid throughout the entire interior of a housing of satisfactory width. Because of this fact, it has been necessary to employ two or more impeller units operating in side by side relation or with their horizontal axes arranged in parallelism. This dual type of impeller mechanism is objectionable because of the increased cost of providing two instead of one impeller units and because of the transmission problem made necessary by the driving of two shafts from a single motor. This transmission mechanism, naturally, either must include inter-meshing gears or one or more belts trained over pulleys. The gearing type of transmission, when operated at a high speed which is essential to obtain a finely atomized fluid traveling at a high velocity, creates a troublesome lubricating problem and is bound to be noisy. Belt transmissions are not entirely satisfactory because of the slippage of the belt, due to stretching and wearing, and because it is impossible to keep the belt dry when operating in conjunction with a device of this character.

50 Impeller mechanisms of the type disclosed in my aforementioned patent and of the type embodying this invention are capable of dispersing or projecting the treatment fluid throughout the entire interior of a rectangular or square housing and yet may employ only one rotatable impeller

unit. These improved mechanisms, therefore, take advantage of all of the desirable features of an impeller having a horizontal axis and overcome all of the disadvantages possessed by the prior art mechanisms of this type.

It is the primary object of this invention to provide impeller mechanisms for effecting washing, rinsing, and/or drying of dishes, silverware, glassware, and the like, which is capable of dispersing or projecting treatment fluid in a finely atomized condition and at a high velocity throughout the entire interior of a rectangular or square housing by means of a single rotatable impeller unit which operates with its axis of rotation arranged horizontally.

A further important object of this invention is to provide impeller mechanisms of the character wherein the treatment fluids are projected throughout a portion of the treatment zone of the associated housing by means of a plurality of rotatable impeller wheels and are projected throughout the remainder of the treatment zone by means of fixed deflectors which, for the most part, cooperate with the rotatable impeller wheels aforesaid insofar as the discharge of the treatment fluid from the fixed deflectors is concerned.

Other objects and advantages of the invention will be apparent during the course of the following description.

In the accompanying drawings forming a part of this specification and in which like numerals are employed to designate like parts throughout the same,

Figure 1 is a transverse vertical sectional view illustrating the action of the impeller mechanisms of this invention in projecting the treatment fluid at a high velocity and in a finely atomized condition so that all portions of the interior of the housing will fall within the effective range of the impelled fluid;

Figure 2 is a fragmentary, top plan view of one form of impeller mechanism embodying this invention;

Figure 3 is a fragmentary, side elevational view of the mechanism disclosed in Fig. 2;

Figure 4 is a detail vertical sectional view of the mechanism disclosed in Figs. 2 and 3;

Figure 5 is a similar view to Fig. 2 but illustrates a modified form of impeller mechanism;

Figure 6 is a similar view to Figs. 2 and 5 but illustrates a still further modified form of impeller mechanism;

Figure 7 is a detail perspective view showing the specific type of impeller wheel employed in the modifications disclosed in Figs. 5 and 6;

Figure 8 is a detail transverse sectional view taken on the line 8—8 of Fig. 10 and illustrates a still further modified form of impeller mechanism;

Figure 9 is a detail transverse sectional view taken on the line 9—9 of Fig. 10;

Figure 10 is a fragmentary top plan view of a modified form of impeller mechanism disclosed in Figs. 8 and 9;

Figure 11 is a fragmentary top plan view of still another modified form of impeller mechanism but reversed end for end with reference to the disclosures of Figs. 2, 5, 6, and 10 for the purpose of better illustrating the construction; and

Figure 12 is a fragmentary side elevational view; partly disclosed in section, of the impeller mechanism illustrated in Fig. 11.

In the drawings, wherein for the purpose of illustration are shown the preferred embodiments of this invention, and particularly referring to the

disclosure of Fig. 1, the reference character 15 designates in its entirety the main body portion of the washing machine housing. This main body portion is open at its top and is adapted to 5 be closed by the removable cover 16.

Referring particularly to the main body portion 15 of the housing, the bottom wall of the same is formed by an aluminum casting 17 having an upstanding marginal flange 18. Extending 10 longitudinally of the bottom 17 is a shallow trough 19 which is adapted to cooperate with a rotatable impeller unit in a manner to be described at a later point. It might be stated at this point that the impeller mechanism which is 15 actually illustrated in Fig. 1 is the mechanism which is disclosed in detail in Figs. 2 to 4, inclusive. It is to be understood, however, that all of the remaining impeller mechanisms are to be 20 operatively associated with a housing of the character disclosed in Fig. 1 and for that reason the present description of Fig. 1 is intended to apply generally to all of the different mechanisms.

The trough 19, at the discharge side for the impeller wheels, which are to be described specifically in connection with each one of the impeller mechanisms, is provided with an upstanding flange 20 which functions as a dam to prevent the treatment fluids which have been returned to the bottom of the housing from flowing back into the trough 19 along the operating zone of the rotatable impeller wheels. This flange 20 is of less length than the length of the trough 19 and terminates at its opposite ends short of the end walls of the housing to provide at the opposite 35 ends of the trough return passageways. These return passageways are not illustrated in Fig. 1 but are disclosed in Figs. 2, 3, 5, 6, 10, 11, and 12 and will be identified in these various figures by means of the reference character 21. Fig. 1 40 clearly illustrates the remaining side of the trough 19 as having unobstructed communication with the bottom of the housing.

All of the impeller mechanisms embodying this invention include a plurality of axially spaced impeller wheels which are mounted on a common 45 horizontal shaft that extends longitudinally of the trough. This shaft will be identified throughout the several figures by means of the reference character 22. This impeller shaft is journaled at its opposite ends in bearings 23 which are positioned so that the bearing openings will be located above the maximum fluid 50 level during all types of operation of the mechanism. One end of the impeller shaft 22 projects through an end wall of the housing, as at 22a, for connection with a prime mover, not shown, which will operate to drive the impeller shaft at a high speed. It has been determined that the speed of rotation of the impeller shaft, in each one of the impeller mechanisms, may 55 range from 1750 to 3500 R. P. M. The most efficient speed, however, has been determined to lie between 3000 and 3500 R. P. M.

The axially spaced impeller wheels of the several mechanisms embodying this invention will 60 function to impel or discharge fluid received from the trough 19 in a highly atomized condition and at a high velocity throughout a certain portion of the treatment zone provided by the entire 65 interior of the housing 15 with its cover 16. This portion of the treatment zone provided or supplied with material by the impellers extends from the point 24 to approximately the point 25. This portion of the treatment zone will be referred to 70 hereinafter as the impeller portion of the treat-

ment zone. The various impeller mechanisms of this invention also include fixed deflector elements which function to receive treatment fluids from the trough 19 and to guide and direct such fluids so that they will be delivered into the remaining portion of the treatment zone; i. e., the portion of the treatment zone which extends from the point 25 around to approximately the edge of the trough 19. This second treatment zone will be referred to hereinafter as the deflector portion of the treatment zone.

Fig. 1 discloses in the impeller portion of the treatment zone fluid movement which is substantially tangential of the impeller shaft 22. The finely atomized particles of treatment fluid travel in straight line flow paths through this impeller portion of the treatment zone. Fig. 1 discloses arrow lines in the deflector portion of the treatment zone which are intended to indicate that the finely atomized fluid particles travel through curved paths in this portion. It has been determined that this travel of the fluid particles through curved paths is not produced as a result of the pull of gravity or as a result of the particles striking against the inner surface of the housing and cover wall and being deflected downwardly. The velocity of the particles traveling through these curved flow paths is too high for either of these actions to take place. It is very obvious that the high speed of rotation of the impeller wheels will bring about or cause a circulation of air within the housing and the cover. Air movement is possible because the interior of the housing is not completely filled with treatment fluid in condensed form for the fluid is, as has been stated, in a finely atomized condition. Unquestionably, this movement of air within the housing creates a low pressure or suction zone or area which increases in intensity or value as it approaches the receiving side of the trough 19, and it is considered that this low pressure or suction condition operates to pull the particles of fluid delivered from the ends of the deflectors with the result that the fluid particles traveling through the deflector portion of the treatment zone will be drawn from their normal straight line flow paths and be compelled to travel through curved flow paths. It will be appreciated that the deflector portion of the treatment zone may be widened or narrowed as desired by shaping the deflectors so that they will point toward different portions of the width of the top wall of the cover. In other words, the deflector blades might be straightened out more than they are disclosed in any of the figures and thereby cause the fluid delivered by the deflectors to cover a greater width or a greater portion of the width of the treatment zone. On the other hand, the deflectors might be curved to a greater extent with the result that the fluid particles discharged from the deflectors will cover a narrower portion of the treatment zone. The deflectors, therefore, should be so shaped or curved that they will start in where the impeller portion of the zone stops.

Coming now to the deflector mechanisms illustrated in detail in Figs. 2 to 4, inclusive, the impeller shaft 22 has suitably secured thereto, as by means of the set screws 26, a plurality of axially spaced impeller wheels 27. Each one of these impeller wheels includes four equi-spaced, radially curved blades 28. The impeller shaft 22 is clearly illustrated as being positioned off center with respect to the width of the trough 75

19; i. e., the axis of the impeller shaft is located closer to the discharge side of the trough than it is to the receiving side. The spacing of the impeller wheels is considered to be very important. It has been determined that they must be spaced from approximately one-half of an inch to approximately one and one-half inches from each other and that the best results are obtained when they are spaced approximately one inch apart. The impeller wheels preferably should be approximately three inches in diameter. The most effective speed of operation of the impeller wheels has been set forth above. The impeller shaft with its impelling wheels should be rotated 15 in a clockwise direction when viewed as in Fig. 1. The impeller shaft should be mounted so that the tips or extremities of the blades 28 should clear the inner surface of the upstanding flange 20 by approximately one-sixteenth of an inch 20 and should clear the inner bottom surface of the trough 19 by approximately three-sixteenths to one-quarter of an inch.

Figs. 2 and 3 disclose in detail the provision of an upwardly curved deflector blade 29 arranged between each adjacent pair of impeller wheels 27. These deflector blades are seated at their lower ends in pockets formed in the inner face of the flange 20 and are secured in place by means of screws, or the like, 30. This manner of mounting the deflector blades is clearly illustrated in Figs. 3 and 4.

Fig. 4 clearly discloses the deflector blades 29 as being formed as a continuation of the curved inner surface of the trough 19.

35 The action of the impeller wheels 27 and the deflector blades 29, in projecting the treatment fluid throughout the entire interior of the treatment zone provided by the housing 15 with its cover 16 has been determined to be as follows:

40 Fig. 1 discloses the level of the fluid in the housing bottom 17 during operation of the impeller mechanism. It will be noted that the liquid level is very low in the trough 19 and in the right hand portion of the bottom of the housing. 45 The level of the liquid is much higher in the left hand portion of the housing. This difference in level in the two different portions of the housing bottom is due to the use of a flange 20 which restricts the return flow of the fluid from the left hand portion of the housing bottom to the trough 19. When the impeller mechanism is in operation, there will be only a comparatively shallow film of water, or the treatment fluid, in the trough. It is very apparent 50 that the impeller blades 28 will dip fluid from the trough 19 and will project the picked up fluid tangentially outwardly throughout the impeller portion of the treatment zone, or between the points 24 and 25. As the water is expelled from the trough, and returns to the bottom 17 of the housing, it will drain back into the trough from the left hand side of the bottom through the end passages 21. The fluid will also drain 55 into the trough throughout the operating zone of the impeller wheels from the right hand side of the housing bottom, and it will also be sucked or drawn into the trough from the right hand side of the housing bottom due to the suction 60 created by the rapidly rotating impeller wheels.

65 It has been determined that the treatment fluid which is delivered or projected by the fixed deflector blades 29 reaches the blades as a result of the action of the impeller wheels in creating low pressure areas between the paths of rotation of the impeller blades, or in the zones

occupied by the fixed deflector blades. In other words, any type of fluid, such as air, water, or the like, which occupies or is positioned within the spaces between the rapidly rotating impeller wheels will be set in motion by the blades of the wheels and will be caused or compelled to travel with the impeller blades. The fluid, arranged between the impeller wheels, which is set in motion by the impeller blades of the wheels, will not be permitted to travel with the fluid projected by the impeller blades after leaving the bottom of the trough, for the fixed deflector blades 29 will receive this fluid and will direct it over to the deflector portion of the treatment zone. The fluid delivered from the deflector blades 29 will be substantially as finely atomized as the fluid projected by the impeller blades, and it will travel at substantially the same velocity as the fluid projected by the impeller blades. Another source of supply of fluid for the fixed deflector blades 29 is provided as a result of side slip of fluid from the impeller blades. If the impeller blades have their front faces extending truly axially of the impeller shaft, a uniform amount of slippage will occur in both directions from each blade; therefore, each blade will supply treatment fluid to the deflector blades positioned on both sides of each impeller wheel.

In Fig. 7 there is disclosed a modified form of impeller wheel. This wheel includes four equi-spaced blades 28a which are curved radially. These blades, however, are tapered transversely or in the direction of the axis of the impeller shaft. This transverse tapering of the impeller blades will cause the front or leading faces of the blades to be angularly arranged with respect to the axis of the impeller shaft. Side slip of fluid from the blades 28a, therefore, will be entirely in one direction, or toward the thin edge of each blade. This type of impeller wheel is employed in each one of the two modified forms of impeller mechanism disclosed in Figs. 5 and 6.

In addition to this impeller modification, Fig. 5 discloses the fixed deflector blades 28a as being arranged in radial alignment with the impeller wheels 27a with their tapered impeller blades 28a. With this arrangement of impeller wheels and deflector blades, the fluid resulting from side slip from the impeller blades will be thrown off tangentially into the impeller portion of the treatment zone. The fluid delivered from the tips or ends of the blades will be received by the deflectors and will be directed into the deflector portion of the treatment zone. The fluid set in motion in the spaces between the impeller wheels will be delivered with the side slip fluid into the impeller portion of the treatment zone. In other respects, the impeller mechanism of Fig. 5 operates in the same manner as the impeller mechanism of Figs. 2 to 4, inclusive.

In Fig. 6, the deflector blades 29b are arranged with respect to the impeller wheels 27a and their impeller blades 28a so that the said fixed deflector blades will half overlap the impeller blades in a radial direction and half overlap the spaces between the impeller wheels.

With this arrangement, the impeller portion of the treatment zone will receive fluid partly from the tips or extremities of the impeller blades and partly from the spaces between the impeller wheels. The deflector portion of the treatment zone will receive its fluid from the deflector blades 29b and the fluid controlled as to its direction of travel by the deflector blades will come in parts directly from the tips or extremities of the im-

peller blades, partly as a result of side slip from the impeller blades and partly from the fluid set in motion between the impeller wheels. Otherwise, the impeller mechanism of Fig. 6 operates in the same manner as the mechanism of Figs. 2 to 4, inclusive.

Figs. 8 to 10, inclusive, disclose a still further modified form of impeller mechanism. In operation, this mechanism of Figs. 8 to 10, inclusive, is identical with that of my aforementioned patent. The structural difference between this impeller mechanism and that of my patent resides in the forming of the deflector blades as an integral part of the cast aluminum bottom 17a of the housing. In casting the aluminum bottom 17a, the mold part which forms the interior or inner side of the bottom is recessed to form the upwardly projecting portions 31 of the deflector blades. The portions 32 of the deflector blades, which extend through or bridge across the trough 19a, also are formed by recesses provided in the upper mold part. These bridging portions 32 are cored at 33 to provide an uninterrupted flow of treatment fluid throughout the entire length of the trough. The impeller wheels 27 are the same as those disclosed and described in connection with Figs. 2 to 4, inclusive. They include four radially curved impeller blades 28.

As is fully described in my aforementioned patent, the treatment fluids are expelled from the trough 19a over the top edge of the flange 20a into the impeller portion of the treatment zone by means of the impeller wheels 27. The integral deflector blades, formed by the portions 31 and 32, receive fluid as the result of side slip from the blades 28 and fluid also runs on to the top surfaces of the deflector blades from the right hand portion of the bottom of the housing. The treatment fluid discharged from the extremities of the deflector blades will be dispersed throughout the deflector portion of the treatment zone. A more complete description of the mode of operation of the impeller mechanism disclosed in Figs. 8 to 10, inclusive, will be found in my aforementioned patent to which reference is hereby made.

Figs. 11 and 12 disclose a still further modified form of impeller mechanism in which one set of impeller wheels is employed for dispersing the finely atomized treatment fluid throughout the impeller portion of the treatment zone while a second set of impeller wheels is employed for providing the deflectors with fluids to be directed to and dispersed through the deflector portion of the treatment zone.

In this modification, the trough 19 is not obstructed in any way throughout its entire length by the deflector blade portions. The alternate impeller wheels 34 dip fluid from the trough 19 and project the same over the top edge of the flange formation 35. The remaining impeller wheels 36, positioned between adjacent pairs of impellers 34, dip fluid from the trough 19 and deliver the same to the inner surfaces of the upstanding, integral deflector blades 37. These deflector blades are shaped so as to direct the fluid received thereby into the deflector portion of the treatment zone.

It is to be understood that the forms of this invention herein shown and described are to be taken as preferred examples of the same, and that various changes in the shape, size, and arrangement of parts may be resorted to without departing from the spirit of the invention or the scope of the subjoined claims.

Having thus described the invention, I claim:

1. A dish and silverware washing, rinsing, and drying machine comprising a housing having a shallow trough in the bottom wall thereof, a flange of less length than and centrally positioned along the discharge side of said trough, a plurality of laterally spaced deflector blades connected to said flange to project only upwardly therefrom, and rotatable means including a plurality of impeller blades arranged to dip into the trough for setting in motion fluid from said trough, a portion of said fluid being discharged directly from said impeller blades at a high velocity and in a finely atomized condition throughout a portion of the interior of said housing extending from the flanged side of the trough, another portion of said fluid being delivered to said deflector blades and discharged therefrom at a high velocity and in a finely atomized condition throughout the remainder of the interior of said housing.

2. A dish and silverware washing, rinsing, and drying machine comprising a housing having a shallow trough in the bottom wall thereof, a flange of less length than and centrally positioned along the discharge side of said trough, a plurality of relatively short and narrow, longitudinally curved, laterally spaced deflector blades connected at their lower ends to said flange to project only upwardly therefrom, and rotatable means including a plurality of axially spaced, radially curved impeller blades arranged to dip into the trough for setting in motion fluid from said trough, a portion of said fluid being discharged directly from said impeller blades at a high velocity and in a finely atomized condition throughout a portion of the interior of said housing extending from the flanged side of said trough, another portion of said fluid being delivered to said deflector blades and discharged therefrom at a high velocity and in a finely atomized condition throughout the remainder of the interior of said housing.

3. A dish and silverware washing, rinsing, and drying machine comprising a housing having a shallow trough in the bottom wall thereof, a flange of less length than and centrally positioned along the discharge side of said trough, a plurality of laterally spaced deflector blades connected to said flange to project only upwardly therefrom, means for detachably connecting said deflector blades to said flange, and rotatable means including a plurality of impeller blades arranged to dip into the trough for setting in motion fluid from said trough, a portion of said fluid being discharged directly from said impeller blades at a high velocity and in a finely atomized condition throughout a portion of the interior of said housing extending from the flanged side of the trough, another portion of said fluid being delivered to said deflector blades and discharged therefrom at a high velocity and in a finely atomized condition throughout the remainder of the interior of said housing.

4. A dish and silverware washing, rinsing, and

drying machine comprising a housing having a shallow trough in the bottom wall thereof, a flange of less length than and centrally positioned along the discharge side of said trough, a plurality of laterally spaced deflector blades connected to said flange to project only upwardly therefrom, and rotatable means including a plurality of axially spaced impeller blades carried by a common shaft and arranged to dip into the trough for setting in motion fluid in said trough, said deflector and impeller blades being arranged entirely out of radial alignment with each other, a portion of said fluid being discharged directly from said impeller blades at a high velocity and in a finely atomized condition throughout a portion of the interior of said housing extending from the flanged side of the trough, another portion of said fluid being delivered to said deflector blades and discharged therefrom at a high velocity and in a finely atomized condition throughout the remainder of the interior of said housing.

5. A dish and silverware washing, rinsing, and drying machine comprising a housing having a trough means in the bottom portion thereof in which treatment fluid may accumulate to be dispersed throughout the housing, means projecting upwardly from a portion of the discharge side of the trough means to a higher level than the remaining side, a plurality of laterally spaced deflector blades joined to said upwardly projecting means at the discharge side of the trough, said deflector blades projecting only upwardly therefrom, a rotatable shaft extending longitudinally of the trough means, and a plurality of impeller blades mounted on said shaft to rotate therewith for setting in motion the fluid accumulating in said trough means, said fluid being dispersed throughout the interior of the housing from the impeller blades and the deflector blades.

6. A dish and silverware washing, rinsing, and drying machine comprising a housing having a trough means in the bottom portion thereof in which treatment fluid may accumulate to be dispersed through the housing, means extending upwardly from a portion of the discharge side of the trough means to a higher level than the remaining side, a plurality of laterally spaced, longitudinally curved deflector blades joined to said upwardly extending means on the discharge side of the trough and projecting only upwardly therefrom, said trough means, including said upwardly extending means, and the curved deflector blades presenting a continuous curved inner surface, a rotatable shaft extending longitudinally of the trough means, and a plurality of impeller blades mounted on said shaft to rotate therewith for setting in motion the fluid accumulating in said trough means, said fluid being dispersed throughout the interior of the housing from the impeller blades and the deflector blades.

DONALD E. YOCHEM.
